UNITED STATES PATENT OFFICE.

LOUIS GODDU, OF WINCHESTER, ASSIGNOR TO JAMES W. BROOKS, OF CAMBRIDGE, AND FRANK F. STANLEY, OF SWAMPSCOTT, MASSACHUSETTS, TRUSTEES.

MACHINE FOR INSERTING SCREW-THREADED WIRE INTO THE SOLES OF BOOTS OR SHOES.

SPECIFICATION forming part of Letters Patent No. 478,056, dated June 28, 1892.

Application filed September 14, 1891. Serial No. 405,664. (No model.)

To all whom it may concern:

Be it known that I, LOUIS GODDU, of Winchester, county of Middlesex, State of Massachusetts, have invented an Improvement in 5 Machines for Inserting Screw-Threaded Wire into Soles of Boots and Shoes, Leather, &c., of which the following description, in connection with the accompanying drawings, is a specification, like letters on the drawings representing like parts.

This invention has for its object to improve that class of machine represented in United States Patent No. 171,610, dated December 28, 1875. The machine described in said patent 15 has a spindle which receives a single-threaded wire which is fed out through the nose at the end of the said spindle by gripping and feeding rolls, and the wire is inserted into the stock resting on a suitable horn or support, the wire 20 while being inserted being rotated so that the threads thereon are screwed into the stock. The wire, having been inserted into the sole, is cut off flush with the sole, leaving a fastening therein. In the machine referred to the 25 spindle is rotated continuously, and the gripping and feeding rolls carried by the spindle at the lower end thereof have imparted to them an intermittent movement in the direction to feed the wire from the nose at the end 30 of the spindle, they being moved once during each rotation of the cam-shaft. The gripping and feeding rolls referred to derive their intermittent movements from a cam on a cam-shaft driven from the worm on the spindle referred to. In the machine described the spindle is mounted in bearings in a head, and the 35 weight of the wire, added to the weight of the head and its parts, results in very considerable strain being put upon the machine when 40 the head has its rising and falling and also its lateral vibrating movements, as when the shoe is being fed, and because of its weight it has been found impracticable to rotate the spindle above a certain speed and do good work. 45 Owing, however, to the great competition in the manufacture of shoes it became a great desideratum to increase the effective speed of operation of the machine referred to, as such increase of effectiveness lessens the cost of production of boots and shoes thereon. In my

attempts to solve this problem and increase the effectiveness of the particular machine under consideration I found that the speed of the spindle could not safely be increased, but rather ought to be reduced; but after considerable experiment I discovered that the cam-shaft actuated by the spindle might be made to rotate at a faster speed, and I therefore provided the spindle with a double worm and altered the teeth of the worm-gear on the cam-shaft, and by so doing I doubled the speed of the cam-shaft, so that it was thus made to actuate not only the gripping and feeding rolls, but the wire-cutting and the head-lifting and head-vibrating or feeding devices, twice during each complete rotation thereof instead of once, as in the patent referred to, and this made it possible to reduce the speed of rotation of the spindle and yet do nearly double the amount of work. To further aid in making the said machine more efficient as to the amount of work produced thereon, I have been able in its changed conditions, to be described, for the first time to utilize my two-threaded wire, (represented in United States Patent No. 370,136,) 75 the said wire having a steeper pitch than the single-threaded wire which has always been used in the patented machine.

Figure 1 in side elevation represents a sufficient portion of a machine embodying my invention to enable the same to be understood. Fig. 2 is a front elevation of the parts shown in Fig. 1. Fig. 3 is a left-hand side elevation of the parts shown in Fig. 1, but with the spindle rotated about ninety degrees 80 from its position shown in Fig. 1. Fig. 4 is an enlarged detail showing the wire-carrying spindle with its attached wire-feeding devices, the double worm and the worm-gear supposed to be upon the cam-shaft. Fig. 5 85 shows the worm-gear developed or laid out flat; and Fig. 6 is a longitudinal section of the spindle and its parts, the worm being omitted, the scale being the same as in Figs. 1 and 3.

The patent referred to was reissued as No. 7,033, April 4, 1876.

The standard C; the spindle D, through which the threaded wire to be used is fed, it being taken from a suitable spool F; the pul-

ley F², fast on the said spindle and rotated by a suitable belt driven by a suitable pulley, (not shown;) the enlargement I at the lower end of the spindle; the feed - rolls II; the 5 toothed slide J; (see Fig. 6;) the threaded sleeve c, connected to the upper end of it and provided with a loose collar c²; the gear f, having a groove equal to one-half of the diameter of the wire, the said groove being opposite a groove in the slide J; the sleeve g, upon which the gear f is mounted; the pawl i, carried by the said sleeve; the ratchet-wheel h, actuated by the said pawl, the said ratchet-wheel being mounted upon a shaft h^x, 10 provided at its opposite end with a pinion j², which engages an intermediate gear j³, which in turn engages a pinion j⁴, fast on one end of one of the gripping and feeding rolls H, having worm-like teeth to engage the threads 15 of the wire; the bearing-plate H², containing the bearings for that one of the grip and feed-rolls which is not rotated positively by the gearing described; the bar m, connected to the loose collar c²; three-armed lever K, having at one end a roller or other stud; the rod n, resting on the stop o; the spring p and sleeve-nut q; the wire-severing cutters s, there being in practice two such cutters; set-screw r; the head E, in which the spindle D has its 20 bearings and which also has bearings for the cam-shaft S; the arms t, one for each member of the cutter; the nose D²; the lever M, instrumental in actuating the arms t, carrying the cutters to cut the wire off close to the surface 25 of the sole; the vertical rod or pin N, (shown by dotted lines in Fig. 1;) the hollow post N²; the arm N³, projecting from the post N² and provided with a roller or other stud; the hollow sleeve B; the vertical rod U; the lever V, to 30 which the upper end of the said rod is adjustably connected, said lever at its inner end having a roller or other stud; the cam L, to actuate the lever K, said cam having a depression 2 (see Fig. 3) and a projection w, (see Fig. 1;) the cam V³, to actuate the lever V; and the cam O, to actuate the rock-shaft N to swing the head E laterally to effect the feeding movement of the shoe being nailed, are and may be all as in the said Reissued Patent No. 45 7,033, where the like parts are designated by

like letters, with the exception of the letter S, which is used to designate the cam-shaft.

In accordance with my invention I have provided the spindle D with a worm A, having two threads a a'; and I have provided the 55 cam-shaft S with a worm-gear R², having its worm-teeth sloped and adapted to receive the double threads of the worm, so that the said worm carried by the spindle rotates the shaft S.

In this my present invention by reason of 60 the double-threaded worm, I am enabled to rotate the cam-shaft S at twice the speed at which it is rotated in the patent referred to, and consequently am enabled to vibrate the lever K, which effects the intermitting motion 65 of the wire-feeding devices, and also the lever M to actuate the wire-cutting mechanism, and also the shaft N twice where heretofore it has operated but once, thus practically doubling the effective capacity of the machine. In practice, however, I find it advantageous to somewhat decrease the speed of the spindle D, and even when that is done the efficiency of the machine is greatly increased by reason of my present invention. 70

Having described my invention, what I claim, and desire to secure by Letters Patent, is—

In a machine for inserting screw-threaded wire into soles of boots and shoes, the following instrumentalities, viz: a rotating wire-containing spindle, gripping and feeding rolls carried thereby and adapted to grip and feed the threaded wire longitudinally, wire-cutting devices, a cam-shaft having a worm-toothed gear and cams thereon, as L, V³, and O, means operated by said cams to actuate the said gripping and feeding rolls, the said cutting mechanism and the said head-vibrating mechanism to feed the work intermittently, and a 80 double-threaded worm carried by the said spindle and rotating the said cam-shaft, to operate substantially as described.

In testimony whereof I have signed my name to this specification in the presence of 95 two subscribing witnesses.

LOUIS GODDU.
